WITNESS:

*C. Stanley Brown,
INVENTOR*
BY *Victor J. Evans*

ATTORNEY

Patented June 5, 1928.

UNITED STATES PATENT OFFICE.

CHARLES STANLEY BROWN, OF YOAKUM, TEXAS.

BROKEN-PIPE EXTRACTOR.

Application filed August 16, 1926. Serial No. 129,588.

This invention relates to new and useful improvements in extracting tools and more particularly to a tool of this character which is especially adapted for use in extracting broken pieces of pipe which are threaded into other pieces of pipe and the main object of the present invention is the provision of a device of this character which may be quickly and readily inserted in the end of a broken off pipe and by the use of a wrench or other tool may quickly and readily unscrew the pipe from its relative position.

It is a well known fact that where a threaded pipe has been broken off in a coupling or similar position it is rather difficult to remove the broken piece of pipe and a view of this the main object of my invention is the provision of a tool which is adapted to be inserted in the broken pipe and said tool is provided with suitable gripping teeth whereby upon turning movement of the tool the teeth will be caused to grip the interior of the broken pipe and remove the same upon further turning movement of the tool, said tool being provided with a substantially rectangular gripping surface whereby a wrench or similar instrument may be used for actuating the tool.

With the above and other objects in view the invention consists in the novel features of construction, the combination and arrangement of parts to be hereinafter more fully set forth, pointed out in the claims and illustrated in the accompanying drawings, in which:

Figure 1 is a side elevation of a piece of broken pipe illustrating the application of my improved extracting tool;

Figure 2 is a transverse sectional view taken through a pipe and showing the arrangement of the tool with respect to a broken piece of pipe, prior to its application to said broken piece.

Figure 3 is a sectional view taken on line 3-3 of Figure 1 which shows the tool in gripping position.

Figure 4 is a detail longitudinal sectional view taken through the tool per se.

In carrying out my invention I provide a substantially cylindrical body portion 1 which is formed with a longitudinal cavity 2 preferably substantially V-shaped in transverse section with a perpendicular wall 3 at its outer end which is formed with an open-

ing 3' while its inner end is formed with an inclined wall 4.

Arranged within the cavity is a tapered body member 5 having a convex surface 4' resting within the V-shaped seat of the cavity 2 and which forms the gripping element, the inner end of which is inclined as shown at 6 to conform to the inclination of the wall 4. The gripping member 5 is eccentrically positioned relative to the body 1 and is normally retained in the cavity 2 by the contacting engagement of the walls 4 and 6 and a screw member 7 which passes through the opening 3' in the wall 3 and is threaded in the gripping member 5. The outer surface of the gripping member 5 is formed with a plurality of teeth and the outer end of the gripping member is provided with a projection 5' which extends outwardly so as to bring the outer end of the gripping member flush with the outer end of the body portion 75 end wall 3 as best shown in Figure 4. The gripping member 5 is of a length to extend beyond the outer surface of the body as best shown in Figure 3.

The exterior of the body 1 is formed with groups of teeth 9 and between each group of teeth are cavities 10, thus when the body is inserted into the broken end of the pipe as shown in Figure 1 and slight turning movement imparted to the body the teeth on the gripping member 5 and the teeth on the body opposite the gripping member will be caused to bite into the inner wall of the broken pipe as shown in Figure 3 and thus by imparting turning movement to the tool the broken piece of pipe may be unscrewed from its position. In order to limit inward movement of the body 1 into the pipe, the body 1 is provided with a flange 11 as best shown in Fig. 4.

The tool is formed with a rectangular end 12 which is adapted to be engaged by a wrench or similar tool for imparting movement to the cylindrical body portion whereby to cause the gripping member 5 and the teeth 9 on the body to bite into the inner wall of the broken pipe for unscrewing the same.

It will be apparent that after the gripping member 5 is positioned off center with respect to the cylindrical body, the same will quickly and readily engage with the interior wall of the broken pipe when the tool is

positioned therein so that with slight turning movement of the tool all of the teeth will readily engage the pipe and unscrew and remove the same.

5 It will be apparent from the foregoing that I have provided a simple and inexpensive device which can be quickly and readily inserted in the broken end of a piece of pipe and through turning movement of the tool 10 the broken piece may be quickly and readily moved from its occupied position.

While I have shown and described the preferred embodiment of my invention it 15 will be understood that various changes and alterations may be made for carrying out my invention in practice without departing from the spirit of the invention or the scope 20 of the appended claims.

Having described the invention, what I 25 claim is:

1. A broken pipe extractor of the character described comprising a body formed with a longitudinal recess having an inclined wall at one end thereof and a straight 25 wall at its opposite end with an opening formed therein, a toothed gripping member mounted in the longitudinal recess, means

pivottally mounted in said opening and being detachably secured to said gripping member, teeth formed on said body in group 30 formation and a substantially rectangular portion extending from said body.

2. A tool of the character described comprising a body provided with a longitudinally disposed recess having an inclined inner wall and a straight outer wall formed with an opening, a flange formed on said body, a rectangular portion centrally extending from said flange, a toothed gripping member disposed in said recess, means passing through said opening for pivotally mounting said gripping member, a projection formed on said gripping member and terminating flush with said straight wall, said gripping member being provided with an inclined wall opposite the projection for association with the inclined wall of the recess, and teeth formed in group formation on the outer surfaces of said body for co-operation with the teeth of the gripping 50 member.

In testimony whereof I affix my signature.

C. STANLEY BROWN.
